Inventor

Edgar C. McUpson

UNITED STATES PATENT OFFICE.

EDGAR C. McUPSON, OF WASHINGTON, DISTRICT OF COLUMBIA, ASSIGNOR OF ONE-HALF TO REUBEN B. BROWNING, OF SPARTANBURG, SOUTH CAROLINA.

DESIGN FOR A BADGE.

58,611.

Specification for Design.

Patented Aug. 2, 1921.

Application filed June 22, 1920. Serial No. 390,922. Term of patent 3½ years.

To all whom it may concern:

Be it known that I, EDGAR C. McUPSON, a citizen of the United States, residing in Washington, District of Columbia, have invented a new, original, and ornamental Design for Badges, of which the following is a specification, reference being had to the accompanying drawing, forming part thereof.

The figure is a plan view of a badge, showing my new design.

I claim:

The ornamental design for a badge, as shown.

EDGAR C. McUPSON.
